UNITED STATES PATENT OFFICE

2,048,410

ARTIFICIAL LEG SUSPENDER

James F. Rowley, Chicago, Ill.

Application September 6, 1932, Serial No. 631,877

3 Claims. (Cl. 3—11)

My invention relates to improvements in artificial leg suspenders and particularly suspenders adapted for legs where amputation is above the knee or where the artificial leg consists of upper and lower sections provided with a knee joint. The invention has among its objects the production of a device of the kind described which is simple, effective, efficient, comfortable and satisfactory for use wherever found applicable.

More particularly it has as an object the production of an improved device of the kind described which will maintain the artificial leg on the stump leg in such a manner that the artificial leg is to all intents and purposes a unitary structure with the stump leg, and is securely, firmly and yet comfortably maintained in place, thereby enabling the wearer of the leg to move about with a more natural gait and action, with the device more perfectly cooperating with the controlling apparatus of the leg, which controlling apparatus need not be described herein. With the present suspender device herein described, the leg is at all times maintained in a desired and intended relation with the stump leg and the body of the wearer, the same as if an integral part of the body.

The improved device is particularly designed so that it may be fitted to the body of the wearer of the artificial leg in such a way that the weight of the leg is substantially positively suspended from the great trochanter at the upper part of the femur bone of the amputated leg so that it is not necessary to tighten the belt to a degree causing harmful effects on the body, and when arranged as herein described does not bind on the internal organs in the abdominal cavity. When so adjusted the belt is maintained in place without sagging or possibility of displacement and the artificial leg maintained in a definite relation with the femur. The artificial leg is also maintained and supported at the front, side and back, the preferred construction being substantially a three point suspension carried substantially from a common point on the body, and which is a fixed point relative the stump leg.

Many other objects and advantages of the construction and application of the device will be obvious to those skilled in the art from the disclosure herein given.

To this end my invention consists in the novel construction, arrangement and combination of parts herein shown and described, and more particularly pointed out in the claims.

In the drawing wherein like reference characters indicate like or corresponding parts:

Fig. 1 is a view in elevation of my improved device applied to the wearer of the artificial limb, a portion of the body and artificial limb being shown;

Fig. 2 is a perspective view of the device, the lower ends of the straps being omitted;

Fig. 3 is a side elevation of the device and portion of the artificial leg; and

Fig. 4 is a view in elevation illustrating one method of attaching the strap to the artificial limb.

In the drawing in which one embodiment of the invention is shown, 1 represents a band or belt of a length sufficient to encircle the body of the wearer, 2 being a buckle for securing the ends of the band together and maintaining it on the body. The band 1 is preferably made of webbing or equivalent material which may be readily cleaned and kept in a sanitary condition. The band 1 is shown provided with a reinforcement 3 of leather or other suitable material which is arranged intermediate the ends at a point where it will be at the hip of the wearer adjacent the great trochanter as will be more fully explained hereinafter, the buckle ordinarily being at the front and center of the body when the device is applied. Secured to the belt at the reinforcement are a plurality of flexible straps 4, 5 and 6, these straps being of webbing, heavy elastic or other material suitable for the purpose, and of a length to extend from the belt or band to attaching points below the upper end of the artificial limb. It may be mentioned that this device is particularly intended for use where the artificial leg consists of upper and lower sections, and knee joints, as well as legs where a knee joint is not present. The straps shown are provided with reinforced ends 7 and preferably adjustable, as shown pivotally, secured to the band 1 at the reinforcement 3 by rivets 8. The opposite ends of the straps are connected to the artificial limb 14 at the side, front and back. In Fig. 4, I have shown a suitable flexible connection in which, 10 represents a reinforcement at the end of the strap and 11 the top suitably reinforced and secured to the artificial limb by the rivet 11' or equivalent means. The parts 10 and 11 are provided with hooks 12 and a lacing 13 secures the parts together.

In Fig. 1, I have illustrated in dotted lines the bony structure of the body, 20 representing the ilium and 21 what is known as the crest of the ilium. The femur is indicated by 22 and the head by numeral 23, the numeral 24 designating what is known as the great trochanter. Various

ligaments and muscles extend from the crest of the ilium and ilium to the parts of the femur, some over the great trochanter. Between the crest of the ilium and the great trochanter are portions of these various muscles, tendons, ligaments, etc., which tissues may yield inwardly to some extent when pressure is applied. The belt or band 1 is of a length to encircle the body between the crest of the ilium and the great trochanter, and as shown, is of a width less than the distance between the two. In some instances it may be desired to so form the belt that it not only overlies, but extends at the outer side face of the great trochanter, a pocket or depression being formed in the belt to fit the great trochanter knob. It is desired that the belt be fitted for comfort as well as utility. When the belt or band is secured in position substantially as shown in Fig. 1, it will be noted that the same overlies the great trochanter and is substantially supported therefrom by the interposed tissues. When the artificial leg 14 is applied to the stump leg 15 and secured substantially as shown, it will be obvious that the leg is at all times maintained in a definite relation to the head of the femur and the great trochanter, and in view of the fact that the same is carried from the great trochanter on that side of the body, the stump leg 15 and the leg 14 are secured in a definite relation so that the two are substantially as one or a unitary structure. The belt illustrated is reversible for use where the artificial leg is on the other side than that shown by merely turning it over and reversing the straps to extend as shown but on the opposite side of the body.

It will be obvious that by securing the artificial leg in place in the manner described, it is substantially carried at three points about its circumference; to-wit; the side, front and the back from a definite single point on the body affording what might be termed a three point suspension from a single point. The artificial leg is thus carried the same as a natural leg insofar as movement with the stump leg is concerned enabling the wearer of the leg to move about with a more natural gait and action. While the leg is firmly held in place, yet it is comfortable as it is not, at any time, displaced relative the stump leg. When the straps are of elastic material, the elasticity is such as to nevertheless maintain the leg in place at all times, but to give slightly if necessary, tending to promote comfort.

It will be particularly noted that by substan-

tially carrying the artificial leg from what may be termed a fixed position or point at the upper part of the femur, the controlling mechanism and apparatus for the leg, that is, the lower leg, foot, etc., may at all times work in the intended and prescribed manner so that the wearer has complete control of the lower leg at all times. The controlling mechanism for the lower leg, etc., forms no part of the present invention and need not be described in detail herein.

5

In view of the fact that the belt is more or less directly and positively carried by the great trochanter rather than by merely the frictional engagement of the belt with the body or by compressing the body above the crest of the ilium, it is not necessary to so tighten the belt as to unduly compress or bind the body to an uncomfortable or harmful extent.

Having thus described the invention, it is obvious that various immaterial modifications may be resorted to without departing from the spirit of the appended claims, hence, I do not wish to limit myself to the exact form, construction and arrangement herein shown and described, or uses mentioned.

10

What I claim as new and desire to cover by Letters Patent is:

1. For an artificial leg provided with a body belt operatively connected to the leg, the method of supporting the leg from the body consisting in applying the belt about the body at the trochanter notch and drawing the belt into the notch to rest upon the great trochanter and maintaining it in supporting engagement therewith.

25

2. The method of fitting an artificial leg, having a stump socket and provided with a body encircling belt located adjacent the stump socket and having connecting means extending between the leg and belt, consisting in applying the belt to the body in a position opposite the head of the femur and drawing the same into the trochanter notch to a supporting position on the great trochanter, and fitting the connecting means so that the stump is operatively and snugly maintained in the socket.

35

3. The method of fitting and securing on an amputated stump leg, an artificial leg having a stump receiving socket and provided with a flexible belt attached to the artificial leg, which consists in applying and seating the belt around the body in the trochanter notch and substantially immediately above the great trochanter.

JAMES F. ROWLEY.
